US00D957978S

(12) **United States Design Patent** (10) Patent No.: **US D957,978 S**
Bernard et al. (45) Date of Patent: **** Jul. 19, 2022**

(54) **SET OF BANDS FOR A FITNESS TRACKER**(71) Applicant: **Fitbit, Inc.**, San Francisco, CA (US)(72) Inventors: **Cédric Eric Jean-Edouard Bernard**, San Francisco, CA (US); **Junyong Park**, San Francisco, CA (US); **Eric John Fairbanks**, Lafayette, CA (US); **Benjamin Patrick Robert Jean Riot**, San Francisco, CA (US); **Irina Igorevna Kozlovskaya**, San Francisco, CA (US); **Brian Dennis Paschke**, San Francisco, CA (US); **Chadwick John Harber**, San Francisco, CA (US); **Jonah Avram Becker**, San Francisco, CA (US)(73) Assignee: **Fitbit, Inc.**, San Francisco, CA (US)(***) Term: **15 Years**(21) Appl. No.: **29/771,375**(22) Filed: **Feb. 22, 2021****Related U.S. Application Data**

(63) Continuation of application No. 29/760,763, filed on Dec. 3, 2020.

(51) **LOC (13) Cl.** ..... **11-01**(52) **U.S. Cl.** **D11/3**

(57) **CLAIM**

The ornamental design for a set of bands for a fitness tracker, as shown and described.

DESCRIPTION

FIG. 1 is a top side isometric view of a set of bands for a fitness tracker;

FIG. 2 is a bottom side isometric view thereof;

FIG. 3 is a front side elevation view thereof;

FIG. 4 is a back side elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a cross sectional view of one of the bands taken along line 9-9 in FIG. 7.

The features shown in dash-dash lines in the drawing depict portions of set of bands for a fitness tracker and the broken lines form no part of the claimed design.
